CLAIM

The ornamental design for a flashlight, as shown and described.

DESCRIPTION

FIG. 1 is a top front perspective view of a flashlight according to the present design.

FIG. 2 is a bottom rear perspective view of the flashlight of FIG. 1.

FIG. 3 is a top view of the flashlight of FIG. 1.

FIG. 4 is a bottom view of the flashlight of FIG. 1.

FIG. 5 is a left side view of the flashlight of FIG. 1.

FIG. 6 is a right side view of the flashlight of FIG. 1.

FIG. 7 is a front view of the flashlight of FIG. 1; and, FIG. 8 is a rear view of the flashlight of FIG. 1.

The broken lines immediately adjacent the shade lines in FIGS. 1 and 7 depict the bounds of the claimed design and form no part of the claimed design, while all other broken lines found in the drawings depict portions of the flashlight that form no part of the claimed design.

1 Claim, 7 Drawing Sheets
